WING TYPE BRUSH

Niels E. Nielsen, Summit, N. J., assignor to Newark Brush Company, Kenilworth, N. J., a corporation of New Jersey

Application February 6, 1953, Serial No. 335,410

10 Claims. (Cl. 15—179)

This invention relates to a new form of a brush which is specially adapted for use in cleaning the inside of tubes, mold cavities and relatively small holes in different materials. It is another object of my invention to provide a wing type brush which can be operated by any handy tool such as a small hand drill into which the holder of the brush can be inserted into the chuck of the drill. Another object of my invention is to provide a construction for the purpose just described which can be quickly and cheaply made yet one that is highly efficient in its operation. Another object of my invention is to provide a small brush unit which can be quickly and securely installed in a holder so constructed that various types of brushes can be quickly installed in the holder. Another object of my invention is to provide an improved brush unit construction wherein high carbon and fine iron wire, horse hair, nylon, tampico or cotton may be easily and quickly formed into a unit to go into the same holder. Another object of my invention is to provide a wing brush that can be made in various sizes for assembly in special holder constructions to be described. In the drawings accompanying this specification Figure 1 is an elevational view of one of the wing brushes mounted in a holder, the drawings being about twice the size of a complete structure.

Figure 2 is a view of Figure 1 on the line 2—2.

Figure 3 is a view on the line 3—3 of Figure 2.

Figure 4 is a view on the line 4—4 of Figure 1.

Figure 5 is a view on the line 5—5 of Figure 1.

Figure 6 is a view on the line 6—6 of Figure 1.

Figure 7 is a plan view of the assembly and clamping ring forming an important part of the brush unit.

Figure 8 is a side view of Figure 7.

Figure 9 is a view partly in section of a modified form of construction.

Figure 10 is a view of the parts shown in Figure 9 but in disassembled position.

Figure 11 is a view of one of the parts of Figure 10 but turned 90°.

Figure 12 is a view of the upper member of Figure 10 turned 90°, the bristles being broken off on one end.

In the various views wherein like numbers refer to corresponding parts, 1 is an assembly ring which can be quickly made from a tube of suitable metal. As shown in Figure 3, after the bristles 2 have been inserted into the ring 1 the unit is pressed so that the ring 1 takes the form shown in Figures 3 and 4. It will be clearly seen that this brush unit can be easily and cheaply made and ready for assembly in a suitable holder 3, which is preferably made of strong metal such as a steel rod that may be bored out down to a point 4 adjacent the reduced solid end 5 of the rod, but this is not altogether necessary especially for the smaller sizes of brushes. Preferably the bore at the brush end of the rod 3 has a larger bore 6 for a distance somewhat greater than to the width of the ring 1, down to a point a short distance below a set screw 7. Preferably the tube is slotted at 8 parallel to its longitudinal diameter as shown in Figure 2, but the upper

2

end of the slit 8 is enlarged as indicated at 9 to receive the brush unit which is composed of the ring 1 and the bristles 2. It will be seen from Figures 1 and 2 that the length of the enlarged slit 9 is just sufficient to accommodate the brush unit. After the unit has been installed in the holder 3 as shown in Figures 1—4, the screw 7 is tightened up so as to draw the arcuate portions of the holder 3 toward each other and cause them to grip the brush unit securely in the holder.

10 Since the brush units may be made in different sizes the holders are made in sizes to take the brushes, which has been stated earlier in the specification, are made to be used to clean tubes and cavities of different sizes which can be carried on a template the same as drills and the brush assemblies can be utilized in drill chucks just the same as ordinary drills.

In Figures 9—12, the holder 10 is made of a rod having the same diameter throughout its length with one end threaded at 11 to receive a part 12, threaded at 13 to engage the threads 11 in the holder 10. The part 12 has a conical taper 14 to fit the tapered hole 15 in the part 10. The part 12 has a bore 16 terminating in a transverse slit 17 which extends into the tapered part 14. The bore 16 is adapted to receive the plug end 18 formed from a small ring 1. A large bore 19 is adapted to receive part 20 of a ring, this part carrying the bristles 2. With this construction, after the bristles 2 have been assembled into a ring, as shown in Figures 9, 10 and 12, the brush unit is assembled into the holder part 12 and that then inserted into the main part 10 of the holder, after which the main part 10 of the holder is turned so the screw threads 11 and 13 will draw the part 12 into the part 10 whereby the conical taper 15 acting on the taper 14 will cause the split sections of part 12 to move into strong gripping engagement with the plug end 18 and also a lighter grip onto the part 20 that carries the bristles. We have found this construction to be advantageous as none of the bristles will be broken off by the part 20 which might happen if too great a pressure were applied to said part.

20 The construction shown in Figures 9—12 is especially adapted for making wing brushes much smaller than shown in Figures 1 and 3, in fact the rod 10 may have a knob or handle on its outer end so the brush may be turned directly by an operator's hand where circumstances present themselves.

From the foregoing it will be seen that I have designed a wing type brush that serves many useful purposes.

Having thus described my invention what I claim is:

1. A brush structure including a ring for receiving bristles, said ring being flattened after the bristles have been inserted into the ring to form a unit, a holder comprising a rod hollow for a part of its length and slotted on the diameter of the hollow portion, the rod having a solid end for mounting the holder in a suitable chuck, the end of the holder opposite the solid end preferably having a bore enlargement and an enlargement of said slit, said enlargement bore and slit adapted to receive said bristles unit and means for forcing the two split portions of the rod toward each other to grip said bristle unit.

2. A brush structure including a ring for receiving brush material, said ring and material being flattened to form a wing brush unit, a holder comprising a rod having a solid end to go into a tool chuck, the rod at the opposite end being hollow with a pair of longitudinal slits oppositely disposed extending through the wall of the hollow part, the slits being wider at the end of the holder to receive the brush unit and means for drawing the parts of the rod defined by the slits toward each other to clamp the brush unit in the holder.

3. A brush structure including a ring for receiving

brush material, said ring and material being flattened to form a wing brush unit, a holder comprising a rod having a solid end to go into an operating tool, the rod away from the solid end having two hollow parts divided by two oppositely disposed slits, the hollow parts and slits at the end opposite the solid end being of larger dimension than the rest of the hollow part and slits to receive the brush unit and means for drawing the parts defined by the slits toward each other to clamp the brush unit in operative position.

4. A brush structure including a ring preferably cut from a tube of suitable metal, the ring being filled with a desired brush material, then the ring and material being flattened to form a wing brush unit, a holder having a solid end and an opposite hollow slitted end to receive the brush unit and clamping means for causing the slitted ends to approach each other and securely grip the said unit.

5. A brush structure as set forth in claim 4 further defined in that the flattened ring is located wholly within the said hollow slitted end while only the brush material extends through the slits to form a pair of oppositely disposed brush wings.

6. A brush structure as set forth in claim 4 further defined in that the hollow part of the holder as well as the slits extends from a point near the solid end of the holder to the other end whereby greater resilience is obtained making it easier to install the brush unit in operative position and further defined in that said clamping means is a transversely positioned screw going through and operatively engaging the two slitted parts, the screw preferably being located near the location of the brush in the holder.

7. A brush structure including a ring for receiving brush material, said ring and material being flattened to form a wing brush unit, a holder having one end adapted to go into a tool chuck, the holder having at its opposite

end a slotted part to receive said brush unit and means for forcing said slotted parts toward each other to cause them to grip the brush unit.

8. A brush structure as set forth in claim 7 further defined in that said slotted part of the holder has a tapered conical end to fit a co-operative surface in the main part of the holder and a screw threaded end to engage screw threads in the main part of the holder as and for the purposes described.

10. 9. A brush structure as set forth in claim 7 further defined in that the holder is in two pieces, one of which is slotted to receive the brush unit and a tapered conical surface terminating in a threaded end, the other piece of the holder having screw-threads to receive the threaded end of the first mentioned piece and a tapered conical surface to engage the similar surface of the said one piece for the purpose described.

10. A wing brush unit including a ring for receiving brush material, one part of the ring being formed into a plug, while the other part holds the brush material, a holder having a main part and an end to receive said unit and co-operative adjustable means, between said main part and end of the holder, to cause said end to grip the ring plug harder than the part of the ring carrying the brush material, when said main part is properly operated.
